(57) **CLAIM**

The ornamental design for an candle holder, as shown and described.

DESCRIPTION

FIG. 1 is a perspective top front right view of an candle holder, showing my new design;

FIG. 2 is a front elevation view, wherein a rear elevation view, a right elevation view, and a left elevation view is an identical image thereof;

FIG. 3 is a top plan view thereof; and,

FIG. 4 is a bottom plan view thereof.

The broken lines in the drawings are for purposes of illustrating the portions of the candle holder that form no part of the claimed design.
